UNITED STATES PATENT OFFICE.

MALCOLM L. COSSITT, OF SAN FRANCISCO, CALIFORNIA, ASSIGNOR, BY MESNE ASSIGNMENTS, TO AMERICAN SALES BOOK COMPANY LIMITED, OF TORONTO, ONTARIO, CANADA.

MATERIAL FEED CONTROL FOR IMPRESSION APPARATUS.

Application filed May 16, 1921. Serial No. 469,969.

To all whom it may concern:

Be it known that I, MALCOLM L. COSSITT, a citizen of the United States, and a resident of the city and county of San Francisco, State of California, have made a new and useful invention—to wit, Improvements in Material Feed Controls for Impression Apparatus; and I do hereby declare the following to be a full, clear, concise, and exact 10 description of the same.

This invention relates particularly to an impressionable material feed for autographic registers, typewriting, calculating and bookkeeping machines and to all classes 15 of impression apparatuses.

The principal object of my invention is to provide a new and novel mechanism for maintaining a single sheet or plurality of sheets in superposed relation, in absolute 20 registry during the introduction and passage through apparatuses and devices of the type above described and to provide means whereby suitably located apertures in said sheet or sheets will be made to register.

25 In type impression, recording or duplicating devices used as office equipment, it oftentimes happens that a carbon record of an original record does not have the impressions thereon in the same location as placed on the original. Where the record and second sheets are printed as standard forms, such as bills of lading, receipts and the like, it is desirable that any record made on the original sheet in spaces left for that purpose should likewise appear in a corresponding space on the reference or second sheets beneath. It is the object of this invention to provide a mechanism that will align the original and record sheets prior to writing thereon, whereby the record sheets will be fac-similes of the original. Other objects and advantages will appear as this description progresses.

In this specification and the annexed 45 drawings, the invention is illustrated in the form considered to be the best, but it is to be understood that the invention is not limited to such form, because it may be embodied in other forms, and it is also to be understood that in and by the claims following the description it is desired to cover the invention in whatsoever form it may be embodied.

In the accompanying two sheets of drawings—

55 Figure 1 represents a sectional elevation through an impression apparatus having a material feed applied thereto constructed in accordance with my invention.

Figure 2 represents a sectional plan view 60 of Figure 1.

Figure 3 represents an enlarged cross-sectional view taken through Figure 2 on the line 3—3.

Figure 4 represents a sectional side elevation through Figure 2 taken on the line 65 4—4.

Figure 5 represents a diagrammatic view 70 of the sheets of paper stock in disassembled position.

Figure 6 represents a diagrammatic side elevation of the normal relation between the paper feed rolls.

Figure 7 is a similar view to Figure 6 with the paper stock passing between the 75 pressure and feed rolls.

Figure 8 represents a sectional end elevation of a modified form of paper feed.

Figure 9 represents an end view of the 80 stop pins.

Figure 10 represents a plan view of the stop pins shift bar.

Figure 11 represents a sectional side elevation of Figure 8 in normal inoperative position.

85 Figure 12 is a corresponding view to Figure 11 showing the relative parts in operative position.

In detail the construction illustrated in the drawings comprises a standard form of impression apparatus consisting of a base member 1 and enclosing casing plate 2 hingedly connected to the end wall 3 of the base member at 3'. The opposite end of the base 1 is provided with a vertical wall 4 95 having a spring detent 5 mounted thereon, adapted to engage a latch member 6 secured on the underside of the plate 14. The spring member 5 is provided with a push button 7 for the purpose of disengaging it 100 from the latch and thus permitting the entire casing to be swung on the hinge pin 3' into open position for replenishing the paper supply of rolls 8, 9 and 10 suitably mounted on guide shafts extending transversely within the interior of the casing side 105

walls. The ends of the paper from the various rolls, 8, 9 and 10 are then passed over the edge 11, writing plate 12 and between the material feed mechanism generally 5 designated by the numeral 13 in stacked relationship.

The usual construction of standard impression devices is to have the cover plate 14 of the housing provided with an aperture 16 therein and a writing plate 12 enclosing said aperture but spaced therefrom permitting the sheets of paper to pass between the respective plates 12 and 14. In preparing the register for the initial operating position, the top plate 14 of the casing is lifted permitting the paper stock to be placed on the roll feed of the feeding mechanism, after which said plate 14 is returned to the normal closed position so that the 20 latch 6 engages the spring 5.

The paper feed mechanism comprises a feed roll 18 mounted on a shaft 19 journaled in the side walls 20 and 21 adjacent an end of the casing 2. One end of the 25 shaft 19 is provided with a suitable handle 22 for imparting a rotative movement to the roll 18. The cover plate 14 is provided with a substantially cylindrical housing 24, in alignment with the roll 18, and has the 30 shaft 25 concentrically mounted therein in suitable bearings 26 and 27 formed in the respective end walls of said housing. The shaft 25 is provided thereon with a plurality of rollers 28 and 29 spaced equidistant 35 from the ends of the housing and which are adapted to contact with the feed roll 18 whereby the sheets of material placed between the feed roll 18 and the pressure rollers 28 and 29 are fixedly maintained there- 40 in and movable forwardly or rearwardly with each rotation of the handle 22. Although the material feed mechanism is described particularly with reference to an impression device specifically known as an 45 autographic register, it is to be understood that the said feed mechanism in the modified forms, such as indicated in Figures 8 through 12 inclusive, could be applied equally as well to typewriting, calculating 50 or bookkeeping machines or any type impression device of whatsoever character.

It is standard practice to provide the sheet or sheets of material with aligned holes therein spaced upon predetermined 55 centers for the purpose of accommodating such sheets to standard filing apparatus. In the operation of this device it is desirable that the pressure rollers 28 and 29 be spaced a distance equivalent to the registering 60 apertures provided in the material whereby the periphery of said pressure rollers will project through said apertures into contact with the outer circumference of the feed roll 18. It will be thus seen, by reference to Figure 6, that the pressure rolls 65

and feed roll will remain in frictional contact during which period no forward or rearward movement of the material may be effected. This construction also permits the handle 22 to be rotated without disturbing 70 the position of the aligned sheets over the writing surface 12 holding the same in constant readiness for quick use. To pass the paper from the casing and outwardly so that it may be torn therefrom an auxiliary 75 pressure roller 30 is provided, eccentrically mounted around the shaft 25 and revolvably journaled in the ends 31 of a forked supporting bar 32. The bar 32 has a central projecting stud 33 extending through the top of the housing 24, substantially intermediate the ends thereof, and is provided with a button 34 on the end thereof for binding the extension spring 35 between the underside thereof and the outer face of 80 the housing 24. The auxiliary pressure roller 30 is operated by the operator pressing downwardly on the button 34 against the tension of the spring 35 placing the said roller 30 into contact with the stacked sheets of material as in Figure 7. After the roller 30 has been brought into contact with the paper stock, the operator grasps the handle 22 on the feed roll 18 and rotates the same, forcing the paper in a direction corresponding with the movement of the handle so that the pressure rollers 28 and 29 are forced out of the registering apertures 85 in the material and made to contact with the outer surface of the top sheet. The spacing between the pressure rollers and the feed roll is of sufficient distance that the thickness of the material will effect a frictional engagement between the respective 90 rollers.

Presuming that the auxiliary pressure roller 30 has been placed into contact with the material or paper over the feed roll and the same moved forwardly in the direction of the arrow in Figure 1, the hand of the operator is then withdrawn therefrom permitting the pressure rollers 28 and 29 to function by moving the material forwardly until the next adjacent pair of apertures 110 come into registry with the respective pressure rollers, after which any forward movement of the material ceases. The material that has been fed from the machine is grasped by the operator and torn loose from the supply by lifting upwardly against the cutting edge 40. Further operations of the machine are carried on in the described 115 manner.

The modification illustrated in Figure 8 consists of a housing 24 having the feed roller 18 journaled in the end walls 26 and 27 thereof and provided with a handle 22 for rotating the same. The pressure rollers 28 and 29 are mounted on the cross shaft 120 25 extending transversely within the casing 125 130.

2 having the ends thereof journaled in suitable pivoted brackets 41 and 42 mounted on the cross-rod 43 journaled in the bearings 44 and 45 provided on the side walls 20 and 21. The auxiliary roller 30 is mounted 5 on a cross shaft 46 having its ends bearing in the respective pivoted bracket plates 41 and 42 and is placed intermediate the respective pressure rolls 28 and 29. The pivoted bracket plate 41 is provided with a projecting 10 end 47 in the form of a finger piece to be used by the operator in withdrawing the pressure rolls 28 and 29 from contact with the feed roll 18, or placing the auxiliary roller 30 into contact therewith against the tension of the spring 48. The spring 48 has an end thereof joined to the plate 41 and the opposite end, secured to the casing as at 49. This modified form of feed mechanism 15 could be more readily adapted to typewriting, calculating or bookkeeping machines than the form indicated in Figures 1 through 7. Where in the operation of sheet feed mechanism such as described in this 20 application, it is found that the sheets of material with the aligned holes therein spaced for adaptation to standard filing apparatuses are insufficient to maintain the plurality of sheets of material in registry, 25 additional perforations may be placed therethrough intermediate the first mentioned holes thus permitting alignment of all the sheets of material at shorter intervals.

This device operates as follows:

25 The sheets of material in superposed relation are drawn over the writing surface 12 and passed between the feed roller 18 and pressure rolls 28 and 29 respectively. When placed in the desired position, the pressure rolls 28 and 29 are brought into contact 30 with the material so that the apertures in the said papers register with the respective spaced pressure rollers. In this position 35 rotative movement of the handle 22 will not cause a corresponding movement of the paper. When it is desired to advance the material from the register, the operator grasps the finger member 47 on the pivoted bracket 41 throwing the pressure rollers 40 28 and 29 out of contact with the roller 18 placing the auxiliary roll 30 into contact therewith. The auxiliary roller 18 is held in contact with the material for a sufficient period of time to enable the handle 45 22 to be rotated and the material advanced from the housing 24 after which the pivoted bracket 41 is released and through the tension of the spring 48, the friction rollers 28 and 29 are brought back into contact with 50 the material, forcing the same against the feed roll 18 until the next adjacent pair of spaced apertures in the material come into registry with the respective pressure rollers 28 and 29 when forward movement of the 55 material ceases.

For maintaining the stacked sheets of material in exact alignment during the operation of the feed mechanism, auxiliary means or pins 50 and 51 are provided upon the same centers as the pressure rollers 70 28 and 29 so as to align with the apertures provided. Each of the pin means 50 or 51 are mounted upon spring fingers 52 secured at the end thereof to the underside of the writing plate 12. For the purpose of disengaging the pins 50 and 51, from the apertures in the material and withdrawing them from projecting through the writing plate 12, I have provided the cross shaft 54, having its ends journaled in the opposite side 80 walls 20 and 21 of the casing and provided with crank throws 55 and 56 inserted between each spring member 52 and the underside of the plate 14. The shaft 54 is further bended to provide a throw 57 at right 85 angles to each of the throws 55 and 56 into which the connecting rod 58 is adapted to be secured having its opposite end fixed on pivot bracket 41. Any radial movement of the pivot bracket 41 from the vertical position shown in Figure 11, for the purpose of disengaging the pressure rolls 28 and 29 from contacting with the material, likewise operates the crank throw 57 to impart a similar radial movement to the throws 55 90 and 56 acting to disengage the pins 50 and 51 from the material and to lower them beneath the plane of the writing surface 12. The last described operation is illustrated in Figure 12 so that upon returning the 100 mechanism to its normal position in Figure 11, the pins 50 and 51 are forced upwardly against the underside of the sheets of material to allow registry with the apertures in the material when the same come into 105 alignment therewith.

Having thus described this invention, what I claim and desire to secure by Letters Patent is:

1. A material feeding device such as described consisting of means for passing material from an enclosing casing, and comprising in combination a pair of contacting rotatable rolls; and a roller member having an actuating means thereon and adapted to be depressed into contact with one of said rolls and spring means for resisting a depressing movement of said roller. 110

2. A material feeding device such as described comprising an enclosing casing having material therein; means for passing said material from said casing, comprising in combination a pair of contacting rolls, adapted to have said material pass therebetween; means for rotating one of said rollers and a roller member having an actuating means thereon and adapted to be depressed into contact with one of said rolls and spring means for resisting a depressing movement of said roller. 120

3. A material feeding device such as described for advancing superposed sheets of material comprising, in combination a pair of contacting rotatable rolls; a roller 5 aligned with one of said rolls having an actuating means thereon and adapted to be depressed into contact with said other roll, means for resisting a depressing movement of said roller and a handle for moving said 10 last mentioned roll: 70
4. A material feeding device for impression apparatuses, such as described, for advancing superposed sheets of material, comprising in combination a manually operable 15 roll; a plurality of rollers frictionally engaging material passing over said first mentioned roll and a roller aligned therewith having an actuating means thereon and adapted to be depressed into contact with 20 said manually operable roller and spring means for resisting a depressing movement of said roller. 80
5. A material feed for impression devices such as described comprising in combination 25 a manually operable feed roll; a pressure roll normally in contact therewith; and an aligned roller having an actuating means thereon and adapted to be depressed into contact with said feed roll, and spring 30 means for resisting a depressing movement of said roller. 90
6. A material feed for impression devices such as described comprising in combination a manually operable feed roll; a pair of 35 pressure rolls in contact therewith; and an aligned roll having an actuating means thereon and adapted to be depressed into contact with said feed roll positioned intermediate said pressure rolls, and spring 40 means for resisting a depressing movement of said roller. 100
7. In a device of the class described, the combination of a set of co-operating members for feeding sheets of perforated paper; 45 a roller member having an actuating means thereon adapted to be depressed into contact with one of said co-operating members; and spring means for resisting a depressing movement of said roller. 110
8. In a device of the class described, the combination of a set of co-operating members for feeding sheets of perforated paper; a handle for manually rotating one of said members; a roller member having an actuating 50 means thereon adapted to be depressed into contact with one of said members and spring means for resisting a depressing movement of said roller. 115
9. In a device of the class described, the combination of a set of co-operating members for feeding sheets of perforated paper; a plurality of rollers frictionally engaging 55 the sheets of perforated paper fed from said co-operating members; a roller aligned with said last mentioned rollers, means to depress 120
- said roller into contact with one of said co-operating members and spring means for resisting a depressing movement of said last mentioned roller. 125
10. A material feed for impression devices such as described comprising a casing; a manually operable feed roll journaled in said casing; a pair of spaced pressure rollers rotatably mounted in said casing and in contact with said feed roll; a roller 75 adapted to be depressed into contact with said feed roll consisting of a frame having said roller revolvably journaled therein; a shaft on said frame, slidably guided in said casing; and spring means engaging said 80 shaft for moving said frame roller out of contact with said feed roll. 95
11. A material feeding device such as described, comprising a casing; a pair of shafts arranged in parallel alignment in 85 said casing; rollers on each of said shafts in contact with each other; means for rotating one of said shafts; a frame slidably mounted in said casing having means thereon for effecting manual movement thereof; a roller 90 revolvably journaled in said frame adapted to be moved into contact with one of said first mentioned rollers; and spring means for engaging said frame for resisting movement of said frame roller into contact with the 95 roller of said rotatable shaft. 100
12. A material feeding device, such as described, comprising a casing; a roller shaft rotatably journaled in said casing; means for rotating said roller shaft; a slide member in said casing; a frame on said slide member; a roller revolvably journaled in said frame adapted to be moved into contact with one of said first mentioned rollers; and spring means for resisting manual 105 movement of said frame roller into contact with said roller shaft. 110
13. A material feeding device such as described, comprising a casing; a pair of shafts rotatably mounted in parallel alignment within said casing; means for revolving one of said shafts a friction roller on said rotatable shaft; spaced rollers on said other shaft in contact with said friction roller; an auxiliary roller arranged between 115 said spaced rollers; means for supporting said auxiliary roller eccentrically relative to said spaced rollers, comprising a supporting frame having said roller revolvably mounted thereon; a member slidably guided in said casing and secured to said roller frame for permitting movement of said roller frame relative to said friction roller; and spring means engaging said member for maintaining said frame roller out of contact 120 with said friction roller. 125
14. In a device of the class described the combination of a set of cooperating rollers for feeding sheets of perforated paper and for registering with and extending into the 130

perforations in the sheets whereby the movement of the sheets between the feed rollers is checked, a set of clamping rollers for engagement upon the sheets for moving the sheets for carrying the perforations therein beyond the first mentioned rollers, and means for yieldingly retaining the clamping rollers out of engagement upon the sheets.

10 15. In a device of the class described employing slotted sheets, the combination of a crank shaft, knurled rollers mounted on the crank shaft, a driven shaft adjacent the crank shaft and driven therefrom, rollers on

the driven shaft aligned with the slots in the sheets and of a lesser width than the diameter of the slots in the sheets, engaging the rollers on the crank shaft, a roller loosely and eccentrically mounted on the driven shaft for engagement upon the sheets of paper for clamping the sheets upon a roller on the crank shaft, and means yieldingly retaining the eccentric roller out of clamping engagement upon the sheets.

In testimony whereof, I have hereunto set 25 my hand at San Francisco, California, this 9th day of May, 1921.

MALCOLM L. COSSITT.
